WALTER HAHNEMANN, OF BERLIN-MARIENFELDE, GERMANY, ASSIGNOR TO C. LORENZ
AKTIENGESELLSCHAFT, OF BERLIN, GERMANY

SYSTEM OF MULTIPLE RADIO TRANSMISSION

Application filed January 24, 1928, Serial No. 249,158, and in Germany February 3, 1927.

This invention has reference to a method of multiple radio transmission which may be used for radio broadcasting or for transmission of distant signals.

5 An object of this invention is to prevent any local reduction of received signals due to the interference effect between two or more transmitting stations of the multiple transmission system.

10 Another object of this invention is to provide a method for shifting the nodal lines of the interference pattern of the radiated signal at a rate above the audio frequency so that there will be no point where the node of interference would constantly remain and reduce or eliminate the received energy.

15 A further object of this invention is to reduce the effect of fading of signals at a distant receiving station by causing the signals from the sending stations to change their relative phases or wave length at an inaudible rate, in such a way that the fading from the different stations is not coincident in time.

20 The invention is illustrated more clearly in the appended figures as follows:—

25 Fig. 1 is a plan view of the interference patterns of two stations which are operating at identical wave lengths and at coincident phase relation;

30 Fig. 2 is a diagrammatic illustration in elevation of the signals actually received in the space between the two stations illustrating further the reduction or the elimination of signal at the nodal points of interference, as applied to Fig. 1;

35 Fig. 3 is the interference pattern in plan view for the same two stations that are shown in Fig. 1, with the difference that the stations are here shown operating 180° out of phase;

40 Fig. 4 is a diagrammatic illustration in elevation applied to Fig. 3 with the stations 180° out of phase;

45 Fig. 5 is a plan view of the super-position of the two interference patterns as illustrated in Figs. 1 and 3, to show the method of this invention in eliminating the effect of this interference pattern; and

50 Fig. 6 illustrates the changes in the transmitted signal of one or more stations accord-

ing to the principle of this invention so as to produce the shifting of the interference pattern.

55 In Figs. 1 to 5 inclusive, reference characters A and B represent the location of two broadcasting stations. It has been suggested to use a number of sending stations such as A and B located at suitable distances for the purpose of radio broadcasting, all of these stations operating on identical wave 60 lengths and controlled by a common central station; this system has received the name of multiple broadcasting. The need for this system lies in the fact that the number of available wave lengths for broadcasting purposes is limited, and also in the fact that the use of a plurality of small stations like A 65 and distributed over the territory in question offers the best possibilities for good reception with simple receiving apparatus. This system is therefore preferable to the use of single large power sending stations. The first requirement for practical introduction of such multiple broadcasting telephony 70 is the complete coincidence of all wave lengths of the transmitters in question so as to prevent the relative superposition and heterodyne disturbances of slightly differing wave lengths. A number of suggestions 75 have been made that accomplish this practically.

80 A further phenomenon which becomes apparent with such a multiple broadcasting system is in the appearance of certain local effects, especially half way between two transmitters when the amount of energy is equal; in other cases this local effect is nearer to the less powerful sender. This effect consists in interference action of the oscillations radiated from different stations on each of the wave lengths of the frequency 85 band used for transmission. This interference reduces more or less the energy at the receiving apparatus, causing more or less distortion of the telephonic modulation in such a receiver. With reference to the location of such "dead" places, that is, with disturbed reception, this would be in the form of a family of hyperbolae, shown by the full lines of Fig. 1 and Fig. 3 in the case of only 90 95 100

- two stations. With three or more stations it would consist of a pattern of spots at which the phase and the amplitude of the oscillations radiated from individual sending stations are superposed in a certain manner. A simple superposition would show that at different points surrounding two stations the amplitude and the phase of the electrical oscillations when added together would have different values (see for instance the appended Figures 2 and 4). It is the object of this invention to reduce or make practically harmless the above described disturbance and to make it possible to have clear reception at the above affected spots. The manner of this invention consists of supplying at the transmitter means for causing periodic interference changes in space or time in the district surrounding the sender, which changes occur so rapidly that no disturbing influence takes place at the receiver. This means that the frequency of these periodic changes must lie between the modulation frequency and the carrier frequency. According to the invention this may be achieved for instance by a corresponding periodic, suddenly or gradually repeated influencing of the phase of oscillations of the carrier frequency on one, several, or even all transmitters of the multiple system. In this case it is preferably that the amplitude of the base frequency is kept constant and that the frequency band radiated from the transmitter is not broadened too much. If the individual transmitters are located at a distance equal to a large number of wave lengths of the carrier frequency, then it is possible, according to this invention, to utilize corresponding periodic influencing of the carrier frequency itself (gradual, periodic and continuous phase shifting).
- In Fig. 1, A and B represent two transmitters operating on identical wave lengths, the distance from each other as shown in this example being 16 wave lengths. Both of these stations operate in the same phase so that the picture of the two instantaneous waves can be represented as in Fig. 1 by the full wavy line for station A and the broken wavy line for station B. The interference pattern will therefore occur as illustrated where the lines represent the maximum interference and therefore the minimum strength of reception.
- The distribution of receiving strength along the connecting line A—B is then illustrated in Fig. 2. In this drawing, curves *a* and *b* show the attenuation of received energy from the two transmitters A and B respectively, when operating by themselves, assuming of course that the two senders are of equal strength. Reference character *c* represents the resulting receiving strength from both stations operating simultaneously, taking into account the above described inter-

ference action. As can be readily seen, the district most endangered is near the middle, between the two stations where the received energy is reduced almost to zero, while towards the stations the receiving strength of each respective station relative to the other is gradually increasing so that the reduction or distortion of modulation soon becomes negligible.

In Fig. 3 are illustrated two transmitters similar to Fig. 1, except that the phase of transmitter B is shifted 180° relatively to the phase of transmitter A. In this case the interference lines will be shifted so that now maxima of reception will occur where previously were minima, and vice versa. This is shown in Fig. 3 by the new interference pattern, the lines of which will be seen to be shifted half way between the lines of pattern in Fig. 1.

Fig. 4 shows diagrammatically the distribution of signal strength in the space between the two stations. It can be seen to differ from Fig. 2 by having maxima where Fig. 2 has minima, and vice versa. According to the invention, we may have for example a periodic changing of the phase of radiated wave of one or both stations (in the accompanying example this takes place on station B). The lines of maximum interference, i. e. the strongest reduction or disturbance is thereby subjected to periodic local shifting. In case these changes occur at a sufficiently high cadence not to affect the reception (that is, above the limit of the highest modulation frequency), then clear reception is assured on a receiver at any location. The effect of this shifting of interference pattern is illustrated more clearly in Fig. 5 where the two sets of lines are superimposed. The lines corresponding to Fig. 1 are shown full, those corresponding to Fig. 3 are shown broken. At any point in the broadcasting range it is impossible to have a minimum of signal all the time, since with the shift of the pattern the signal immediately changes to a maximum thus averaging a good strong reception. It is possible to achieve the described more or less sudden continuous changing of phases, for instance, by a rotating coil or condenser or else by any other well-known phase shifting arrangement. An iron core choke coil would be especially suitable, the saturation of such a coil may be changed by alternating current which corresponds to any desired cadence of changes. These choke coils can then influence the self-inductance or capacity in any desired manner, and any particular arrangements, and thereby affect the phase of the oscillating circuit of the transmitter in question.

A periodic change of receiving strength of the additive oscillations at any definite point can be furthermore achieved according to this invention by varying periodically the

carrier frequency of one or several transmitters within certain definite limits (this is equivalent to a gradual change of phase). This may be illustrated as in Fig. 6 where the 5 frequency (and hence the wave length) is changed at each vertical line, representing time intervals of $1/20,000$ second. The change in frequency may be only a very small percentage.

10 This is especially practical when the distance of the stations is large compared with the wave length, since then the changes in wave length need not be very large. Otherwise the wave length band for a definite number 15 of multiple broadcasting transmitting stations would be too large and the manner and advantage of the multiple broadcasting would be thereby set back or lost. The change of the carrier frequency may be secured very simply, for example, by subjecting the tuning of one of the circuits that determines the frequency of the oscillations, such as the anode oscillating circuit of the tube sending arrangement, to a periodic 20 change. Or the change of frequency could be secured for instance, by inclusion in one of the circuits of an iron core coil, the induction of which is changed by a suitably controlled alternating current corresponding in 25 frequency to the cadence at which the desired wave length change will occur. The same can be also achieved by inclusion of a variable condenser operated at a speed to create 30 changes corresponding to the cadence of the desired wave length change.

35 A practical numerical example may be submitted as follows:

The distance of the most affected receiving 40 location relative to the sender, that is, the most dangerous zone, is half the distance between the two stations. If a change in the strength of signal from 0 to about $1/2$ is satisfactory at such a point, then it means that the phase at this point must be changed 45 so that the interference lines (or spots) are shifted about $1/10$ of the wave length. This would mean, in the present example, a wave 50 length change at the sender of $1/10 \times \frac{1}{a}$

55 from which can be easily derived, with $a = \frac{e}{\lambda}$, the number of wave lengths (λ) in the distance (e). Thus, for instance, if the distance between the stations is 100 km., which corresponds to just about the limit of easy 60 reception, then in the middle, between the two stations, the distance from each transmitter would be $e = 50,000$ meters, and therefore with an operating wave length of 300 meters, the required wave length change would be 65 equal to

$$\frac{1}{10} \times \frac{300}{50,000} = \frac{3}{5} \times \frac{1}{1000}.$$

70 75 80 85 90 95 100 105 110 115 120 125 130

75 This means that with the basic wave length

of 300 meters corresponding to a frequency of 1,000,000 per second, it would be necessary to have a frequency change to 1,000,600 per second, and this change may take place at a cadence of 10,000 times per second. The required change of the interference position gives therefore a value which in practice could not be designated as prohibitive or disturbing.

Such an effect as in the above described arrangements can be also achieved according to this invention by modulating the transmitted wave, for instance, at one of the stations, by an intermediate frequency, which is above the audible limit and is therefore not disturbing for reception. What happens then is that the local reception conditions represented by curve e according to Figs. 2 and 4 are changed periodically in cadence with the modulating frequency into the normal continuously extended curves a or b . By this means the reception strength is also changed, without a disturbing effect, while the same result as in the above is achieved. In this connection, when there are, e. g., three stations, it is only necessary to modulate one of these stations by the cadence frequency.

A further useful application of this invention may be described as follows:—

It has been found that short waves (100 meters and less) are quite suitable for very 95 distant transmission, even with a small amount of energy. But unfortunately the received signals are very often subjected to changes commonly referred to as fading, which appear to be dependent on quite a number of different factors, such as the time of day, the time of year, the wave length, atmospheric conditions, etc. A special instance of eccentricity of fading is the fact that during 100 the daytime a certain wave length is best, and at night another wave length is best. The facts of fading are sometimes explained as follows:—

In the case of a single wave length being transmitted from a single station to a single 110 receiving station, the radiation may find two or more paths of differing lengths so that the waves arriving over the different routes will be out of phase. The plurality of different paths is then explained by the presence of reflecting or refracting ionized layers (commonly called Heavyside layer).

There have been therefore, attempts to 115 120 make the distant reception independent of these changes by simultaneous transmission on several different wave lengths, so as to maintain the legibility for a longer period of time.

According to the present invention, another way is suggested, which as distinct from the previous methods does not combat the eccentricities of fading by actually changing the wave length being transmitted or by simultaneously transmitting two wave lengths on the chance that one of the two will get

through. Instead, a plurality of transmitting stations at different locations is employed, all using the same wave length. A plurality of receiving stations might be employed or both the sending and receiving stations might be pluralized.

But such short wave multiple transmission or reception without the inclusion of the present invention is impractical because the different lengths of the short wave routes would cause the waves to get out of phase and form nodal points. An interference pattern is therefore formed at the receiving location similar in certain respects to the one described above. While at a certain distance there exists the addition of energy arriving along different routes, for another distance there is a subtraction. To attempt to move the station from such a point of signal 20 would be futile because the various short wave routes are always varying in length due to the effects of light, darkness and the weather on the assumed Heavyside layer, and due to many other variations not yet understood. In other words, an interference pattern would be formed but it would be shifted fortuitously so as to accentuate rather than eliminate fading. The periods of shifting would probably be well within an audible 25 cadence.

With the application of this invention to multiple short wave sending the above mentioned nodal or interference pattern would be varied at a cadence above the audible 30 range and therefore without effect on modulation oscillations. Thus, all fading or other effects of variations in the length of the short wave paths due to changes in reflecting conditions or other conditions would be eliminated. According to this invention, a number of spatially separated transmitters are provided which are all operating on the same wave length, and are controlled from a common central station. Although this latter arrangement is disadvantageous on account of the increased cost, it may have exceptional technical advantages in many cases in comparison to the large stations operating on long wave length with large energy output. 40 If one of these sending stations is now changed with regard to phase or carrier frequency as described above, then the further effect of the changing interference pattern is introduced and the effect of the above described fading is thereby minimized.

Having described my invention, what I believe to be new and desire to secure and protect by Letters Patent of the United States is:—

1. In a system of multiple radio transmission comprising a number of transmitters operating on identical wave length and producing an interference pattern within the radiated range, a method of reducing the local

disturbing effects of interference which comprises periodically changing the phase on at least one of said transmitters and thereby shifting the interference pattern.

2. A method as specified in claim 1 in which said changing of phase has a cadence above the audible limit.

3. In a system of multiple radio transmission comprising a number of spaced transmitters, normally operating on substantially identical wave lengths and producing an interference pattern within the radiated range, the method of reducing the effect of said interference which comprises periodically shifting the interference pattern by a fraction of the wave length, at a cadence above the limit of audible frequency.

4. In a system of multiple radio transmission comprising a number of transmitters normally operating on substantially identical wave lengths and producing an interference pattern within the radiated range, the method of reducing the local disturbing effects of interference which comprises changing the carrier frequency of the radiation at one of said transmitters to produce a continual gradual change of phase of said transmitters and a resulting gradual shifting of said interference pattern.

5. A method as specified in claim 4 in which said changing of carrier frequency has a cadence above the audible limit.

6. In a system of multiple transmission comprising a number of spaced transmitters operating on substantially identical wave lengths and producing an interference pattern within the radiating range, the method of reducing the effect of said interference which comprises periodically shifting the interference pattern by a fraction of the wave length at a cadence above the limits of the signalling frequency.

7. The method of eliminating fading which comprises operating a number of wave transmitters of substantially identical wave lengths and periodically changing the phase of the radiated wave from one of said stations at a cadence above the limits of the signalling frequency.

8. The method of eliminating fading which comprises operating a number of wave transmitters of substantially identical wave lengths and periodically shifting the wave lengths of one of the stations by a fraction of a wave length at a cadence above the limits of the signalling frequency.

9. The method of eliminating fading which comprises operating a number of wave transmitters of substantially the same frequency and changing the carrier frequency of one of these transmitters at a cadence above the limits of audibility.

10. In a system of multiple radio transmission comprising a number of transmitters

operating on substantially the same wave lengths and producing an interference pattern within the radiated range, the method of reducing the local disturbing effect of interference which comprises changing the carrier frequency of the radiation at one of the transmitters at a predetermined frequency.

5 In testimony whereof I have affixed my signature.
